DESCRIPTION

FIG. 1 shows an isometric view of an elevated planter box with transparent cover, showing the invention;

FIG. 2 shows an isometric top view of the planter box portion thereof, shown at an enlarged scale;

FIG. 3 shows an isometric side view of the cover portion thereof;

FIG. 4 shows an isometric side view of the planter box and cover portions thereof;

FIG. 5 shows an isometric bottom view of the planter box portion thereof; and,

FIG. 6 shows an isometric view thereof, shown with the cover separated.
